UNITED STATES PATENT OFFICE.

NICOLAAS NOBEL, OF PASOEROEAN, JAVA.

PROCESS OF AND APPARATUS FOR MACERATING SUGAR-CONTAINING MATERIALS.

Application filed August 18, 1926, Serial No. 129,924, and in the Netherlands East Indies September 26, 1924.

It is already known to macerate sugar containing materials such as the bagasse when passing from one mill to the next or the beetroot-shreds when passing from the scrapper (cutting machine) to the pulper. Thereby the bagasse is conveyed by means of a rake-carrier through a receptacle containing the usually heated macerating liquid. Also it is known to apply an inclined receptacle with its highest part at the outlet-side of the carrier, so that a liquid current opposite to the travel-direction of the bagasse may be applied.

Beetroot-shreds are treated in a similar way by means of a diffuser-battery (set of macerating devices) the macerating liquid consecutively being used in the different diffusers starting with the last (nearest to the pulper). Between each two adjacent diffusers the liquid is heated which heating is progressive through the whole battery.

The disadvantages of these known methods are that they require a great space for the apparatus, especially in length for bagasse, a great quantity of the macerating liquid and a considerable amount of time.

It is my object to eliminate the said disadvantages and therefore the process according to the present invention comprises maintaining an abundant liquid flow passing from above to below through a thick mass of the sugar containing material, this mass being moved horizontally and the liquid dripped through, at least the greater part of it, being used again and again for passing through the material.

With bagasse, the same is conveyed e. g. by means of a plank-carrier in a thick blanket (about 75-100 c. m. thick instead of the usual ± 20 c. m.) from one mill to the next next with a velocity of $1/2$ -1 m. p. minute. It will be clear, that by doing so a short distance between the mills is sufficient for the applying of this process, a sufficient macerating being assured by the abundance of the liquid flow and that also a relatively small quantity of liquid is sufficient, due to the fact that same is repeatedly used. Especially the first named advantage of my process is of great interest, as in some places e. g. in most factories in Java, the distance between the adjacent mills is too short for applying the known process.

With beet-shreds, the same are conveyed e. g. by means of receptacles with perforated

bottoms. With such receptacles the conveying may be a step by step motion, the same macerating liquid being repeatedly poured upon the shreds through separate conduits.

My process allows a particular applying of the counter current principle in that the liquid is poured upon the material at different places along the conveying direction, and that the liquid dripping through is received by separate receptacles whilst each receptacle is filled up by the liquid from the adjacent receptacle at the end side of the conveying path (the last receptacle being filled up by fresh liquid) and decreased by conveying a part of it to the adjacent receptacle at the other side (the contents of the first receptacle being decreased for macerating at a previous interval between the mills or for being added to the juice for further treatment or treated separately for sugar-extracting purposes).

Due to the travelling of the material the liquid contained therein is also conveyed to above the next receptacle. Therefore the counter current action according to a further feature of my invention may be improved by applying means for expressing the material preferably a little distance before the places situated above the walls separating the receptacles.

In the accompanying drawing an apparatus according to the present invention is shown by way of an example.

The endless belt 1 of a plank carrier is supported by rollers 2, 3, 4 and 5. Under this carrier three hoppers 6, 7 and 8 are provided above receptacles 9, 10 and 11. Through conduits 12, 13 and 14 the macerating liquid is pumped from these receptacles to points above the mass of the sugar containing material, conveyed by the carrier and allowed to drip down upon such material. The receptacles are connected to each other by open overflow conduits 15 and 16 respectively and the receptacle 11 is provided with an open overflow 17.

For expressing the material an endless belt 18 with its rollers and a drum 19 are provided some distance before the points right above the separation lines between the hoppers.

Before entering next mill, the material is expressed between rollers 20 and 21, the expressed liquid being conveyed through a conduit 22 to the receptacle 9, in which pref-

erably macerating liquid preferably fresh, is supplied through a pipe 23. Before the rollers 20—21 macerating liquid or fresh water may be supplied through a pipe 24.

5 The capacity of the pumps pressing the liquid through the conduits 12, 13 and 14 is such that e. g. each pump conveys 50 L p. sec., the conduits being e. g. of 8" diameter.

The overflow 17 is lower than the overflow 10 16, which is lower than the overflow 15.

A heating of the liquid, known by itself, may be applied e. g. by introducing steam into the conduits 12, 13 and 14.

The working of the apparatus is quite 15 evident from the above.

Having fully described my invention, what I claim is:

1. A process of macerating sugar containing materials which consists in conveying the 20 material in a mass through a course, pouring macerating liquid upon the mass at a number of stages in the course and allowing the liquid to drip therethrough, gathering the drip liquid from said pouring stages, 25 commingling the liquid gathered from the said pouring stages, and returning more or less of the commingled liquid to the said pouring stages and repouring the same upon the mass.

30 2. The process of macerating sugar containing materials which consists in conveying the material in a mass through a course, pouring macerating liquid at a plurality of stages upon the mass and allowing it to drip 35 therethrough, gathering the said drip liquid at a plurality of stages, including a stage adjacent to the exit side of the mass, adding fresh liquid to the gathered drip liquid at said stage, causing the liquid to flow successively from one gathering stage to the other throughout the gathering stages, whereby the liquid is commingled, and conducting the commingled liquid from the gathered stages back to the pouring stages

40 45 and repouring the same upon the mass.

3. A process of macerating sugar containing materials as claimed in claim 1, characterized by the fact that at stages between

the pouring stages the sugar containing material is expressed.

4. Apparatus for macerating sugar containing materials comprising means for conveying the sugar containing material in a thick mass, which means allows the dripping through of liquid, means for maintaining an abundant flow of the macerating liquid upon the said material, and means underneath the said conveying means for gathering the liquid dripped through in such a manner that at least the greater part of it is poured again upon the said material.

5. Apparatus for macerating sugar containing materials comprising means for conveying the material in a thick mass and so as to allow liquid to drip therethrough, means for pouring macerating liquid upon the mass, and means located underneath the said conveying means for gathering the liquid dripping from the mass and returning more or less of it to be poured again upon the material, said means including a series of receptacles arranged in a row in the direction of travel of the material, each receptacle having a device leading therefrom for discharging liquid upon the material, said receptacles being connected for the flow of material from one to the other throughout the row.

6. Apparatus for macerating sugar containing materials comprising means for conveying the material in a thick mass and so as to allow liquid to drip through the mass, a series of receptacles arranged below the conveying means in spaced relation to each other for gathering liquid dripping from the mass, said receptacles being connected with each other for the flow of liquid from one to the other, devices leading from said receptacles for conveying liquid above the mass and pouring it thereupon, and means for expressing the mass of material at points along its length of travel.

In testimony whereof, I have signed my name to this specification.

NICOLAAS NOBEL.
